UNITED STATES PATENT OFFICE.

HORACE G. BAKER, OF HARLAN, IOWA, ASSIGNOR OF ONE-HALF TO WILLIAM H. TOWNSAN, OF HARLAN, IOWA.

AUTOMATIC DISPLAY-RACK.

1,239,662.

Specification of Letters Patent. Patented Sept. 11, 1917.

Application filed November 21, 1914. Serial No. 873,368.

To all whom it may concern:

Be it known that I, HORACE G. BAKER, a citizen of the United States, residing at Harlan, in the county of Shelby and State of Iowa, have invented certain new and useful Improvements in Automatic Display-Racks, of which the following is a specification.

This invention pertains to an improved automatic display rack and more particularly to a device of this character especially adapted for advertising purposes, such for instance, as displaying suitable cards or other articles within a show window.

15 The invention has as its primary object accordingly, to provide a device of this character which will, when set in operation, successively display a plurality of cards or other articles, and so constructed that the said cards will be automatically shifted as they are successively brought into position for display, so that each of said cards at the proper time, will reverse its position to consequently bring its opposite side into position for display and to, at the same time, uncover the next succeeding card for display.

20 The invention has as a further object to provide an improved construction wherein each of the cards or articles being displayed upon initially arriving at the position for display, will be automatically restrained for maintaining the card or article stationary for a suitable length of time, and wherein each of said cards or articles, upon being 25 thus restrained, will automatically restrain the next succeeding card for properly bringing it into position where it will be automatically restrained upon the release of the card immediately in advance thereof.

30 A further object of the invention is to provide a device of this character so constructed as to automatically and successively display opposite sides of each of the cards or articles carried thereby, and wherein each of said 35 cards will, by gravity, be automatically moved to effect this result.

Another object of the invention in this connection, is to provide automatic means for successively moving each of the cards or

articles as they advance into position for 50 display, against the action of gravity, to substantially the highest point of their movement against their tendency to gravitate, to such position that upon the automatic release of each of said cards or articles, they will 55 normally gravitate to effect the reversal thereof.

A still further object of the invention is to provide in an improved device of this character wherein a plurality of cards or 60 articles are being displayed and moved into position for display at a certain rate of speed, an independent card or device moving at a greater rate of speed and so constructed as to normally attract attention.

65 And the invention has as a still further object to provide a construction wherein the cards for display and moving at one rate of speed, and the independent card provided for attracting attention and moving at another and greater rate of speed, will be propelled from the same source of power.

70 Other and incidental objects will appear as the description proceeds and in the drawings, wherein I have illustrated the preferred embodiment of my invention and wherein similar reference characters designate corresponding parts through the several views:—

75 Figure 1 is a perspective view of my improved display rack, illustrating a plurality of cards positioned thereon for display,

Fig. 2 is a vertical sectional view illustrating the mounting of the shaft disposed to operatively support the cards for display, 85 as well as the head carried thereby,

Fig. 3 is a fragmentary elevation particularly illustrating the mounting of the arms employed for supporting the cards and the movement of the said cards when restrained 90 for display,

Fig. 4 is a perspective view of one of the cards employed,

Fig. 5 is a perspective view of one of the arms used in operatively supporting the 95 cards for display,

Fig. 6 is a vertical sectional view illustrating the mounting of the independent

card employed for attracting the attention of an observer,

Fig. 7 is a horizontal sectional view also illustrating the mounting of the card shown 5 in Fig. 6.

Fig. 8 is a perspective view illustrating the sleeve employed for detachably connecting the drive shaft of the device with the shaft operatively supporting the cards for 10 display, the said shaft being partly broken away, and

Fig. 9 is a view illustrating a slight modification of the invention.

Coming now to more particularly describe 15 the invention, I employ a base 10 which may be of any suitable character and to which is secured upon one side a suitable motor. For convenience, I have illustrated the use of a spring motor in the form of clock 20 works indicated as a whole at 11 in Fig. 2 of the drawings, although it is to be understood that I do not wish to limit myself in this regard as any other suitable type of motive power may be employed.

25 It will be seen upon reference to this figure and also upon reference to Fig. 9 that the clock works 11 includes the spaced parallel frame sections 12, which are connected at opposite corners by suitable posts 13. 30 Mounted for rotation upon the sections 12 is a drive shaft 14 having its free extremity 15 squared to receive a key and operatively connected with and surrounding the said shaft is a suitable spring 16. Mounted upon 35 the shaft 14 is a tooth wheel 17 which meshes with the pinion 18 carried by a shaft 19 operatively supported by the said frame sections.

Arranged upon one side of the shaft 19 40 and rotatably mounted upon the frame sections 12 is a driven shaft 20, which projects upwardly upon one side of the adjacent frame section 12. The shaft 20 is provided with a pinion 21 disposed to mesh with the 45 tooth wheel 22 carried by the shaft 19 and is thus operatively connected therewith. Meshing with the tooth wheel 22 is a second pinion 23 which is mounted upon a shaft 24, the shaft 24 being also provided with a 50 tooth wheel 25 disposed to mesh with the pinion 26 carried by the shaft 27, it being understood, of course, that the shafts 24 and 27 are operatively supported by the frame members 12. Arranged upon the 55 shaft 27 is a tooth wheel 28 which meshes with the pinion 29 carried by a governor shaft 30, the shaft 30 being rotatably mounted upon the frame sections 12 and projecting to extend upwardly and laterally upon one side of the adjacent member to detachably receive at its free terminal, a governor 60 31.

The clock works thus described may be detachably secured to the base 10 in any

suitable manner, as by lugs 32 which are 65 formed to receive suitable fastening devices, and inclosing the clock works and resting upon the base 10 is a casing 33. The motor thus presents a neat appearance, it, of course, being understood that the casing 33 70 may be ornamented in any desired manner to enhance the value of the device for advertising purposes, and it will be observed that the governor 31 is disposed exteriorly of the casing so as to be readily visible. 75

At this point, it should be stated that the ratio of gears between the drive shaft 14 and the driven shaft 20 and between the said drive shaft and the governor shaft 30, is such that the governor shaft will rotate 80 at a relatively higher rate of speed than the driven shaft, the shaft 20 being moved rather slowly, while preferably, the governor shaft 30 will turn at a relatively fast rate of speed. The reasons for so connecting the shafts 20 and 30 will presently appear.

The governor 31 preferably includes a relatively straight flat plate 34 which is provided midway its ends, with a socket 35 engaging the governor shaft 30. Arranged upon the plate 34 to extend upwardly therefrom, is a card or other suitable device 36 which, for convenience in the further description of the invention, will be designated an attention device; the object of the card 36 being to arrest the attention of a possible observer.

The card 36 upon one longitudinal edge 100 thereof, is provided with a series of longitudinally spaced and transversely extending slits which define a plurality of tongues 37 which are alternately engaged with the plate 34 upon opposite sides thereof for detachably maintaining the card in position upon the governor. While I have illustrated the use 105 of a card 36 as an attention device, still, it is to be understood that I also do not wish to limit myself in this regard, as any other suitable object or article can be attached to the governor and designed to serve a similar purpose. It is intended that the attention device employed shall bear some distinguishing feature, such for instance as being colored in a peculiar manner, but in the type 110 of attention device which I have shown in the drawing, the card 36 is preferably provided with the word "Look" upon opposite sides thereof and arranged in such position 115 that a possible observer will readily see the word in passing the device, it being remembered that the governor 31 will, when the device is in operation, be rotated at a relatively high rate of speed to further tend to 120 arrest attention.

Having thus described the motor illustrated, and the attention device connected therewith, I shall now proceed to describe

the means employed for operatively supporting the cards or other articles used for successive display.

Detachably secured at one end, to one side 5 edge of the base 10 to abut the adjacent face of the casing 33, is a vertically arranged post 38. The post 38 may be of any suitable material and may be connected with the base 10 in any desired manner as by screws 39. 10 Upon the upper extremity of the post 38, is provided a laterally extending guide arm 40 which projects inwardly over the casing 33 and which is provided adjacent its outer extremity, with a suitable opening disposed in alinement with the drive shaft 20. The guide arm 40 may be formed of any suitable material such as sheet metal and is bent transversely adjacent one end to form a terminal lug 41 extending vertically of the post 20 with the adjacent portion of the arm seating upon the upper extremity of the post. Preferably, the guide arm 40 is detachably connected with the post 38 and is held in position by a suitable fastening device 42 extending through the said arm and into the adjacent end of the post.

Supported for rotation by the guide arm 40 and detachably connected therewith is a standard which, among other features of 30 construction, includes a shaft 43 which passes loosely through the opening formed in the guide arm 40 in alinement with the drive shaft 20. The confronting ends of the shafts 30 and 43 are squared as illustrated in detail in Fig. 8 of the drawings to 35 detachably receive a sleeve 44, operatively connecting the said shafts so that motion imparted to the drive shaft 20 will be communicated to the shaft 43. In this connection, attention is called to the fact that in 40 the provision of the connecting sleeve 44, the standard is detachably mounted in position.

The standard previously referred to is 45 further provided with a head indicated as a whole at 45 in Fig. 1 of the drawings. This head is secured to the upper extremity of the shaft 43 and provides a hub for operatively supporting a plurality of exhibit supporting 50 arms or members, as shall be presently described.

More particularly, the head 45 includes an annular bearing member or disk 46, which may be formed of any suitable material and 55 which is centrally apertured to loosely receive the adjacent extremity of the shaft 43, the said disk being supported, preferably by a nut 47 screw threaded upon the shaft. Bearing over the member 46 in spaced substantially parallel relation thereto, is an annular retaining or guide member 48, the said member being in the form of a disk similar to the disk 46 and being centrally apertured to loosely receive the adjacent extremity of

the shaft 43. Interposed between the members 46 and 48 and removably fitted upon the shaft 43, is a spacing member or washer 49 which supports the member 48.

Removably fitted upon the shaft 43 and resting at one extremity, upon the member 48 is a sleeve 49'. Removably seating upon the opposite upper extremity of the sleeve 49' is an annular member or disk 50 similar to the disks 46 and 48, the disk 50 having a central aperture formed therein to loosely receive the shaft 43. The adjacent upper extremity of the shaft 43 is screw threaded to detachably receive a nut 51 and it will be observed that by properly adjusting the nut 51 upon the shaft 43, the several members 46, 48, and 50, may be rigidly clamped upon the shaft to turn therewith.

From the description just preceding, it will be seen that the head 45 is detachably connected with the shaft 43 and, as illustrated in the drawings, the members 46, 48, and 50, are concentrically mounted upon the shaft. Formed in the peripheral margin of the member 50 is a series of circumferentially spaced concentrically arranged openings and the member 48 is provided with a similarly arranged series of openings, the distance between adjacent openings in the member 48 being equal to the distance between adjacent openings in the disk 50.

The members 48 and 50 are arranged upon the shaft 43 with the openings therein in substantial alinement and oppositely disposed openings then provide pairs of coacting sockets disposed to operatively receive the exhibit supporting arms 52, one of said arms being shown in detail in Fig. 5 of the drawings. The arms 52 are each preferably formed from a length of suitable resilient wire, which is bent intermediate its length to provide a shank 53, from one terminal of which extends at substantially right angles thereto a laterally disposed arm 54, the arm 54 adjacent its free extremity being reversely bent laterally to provide a terminal shoulder 110 55 and having its free end thence returned to extend to a point in substantial alinement with the arm 54.

The shank 53 of each of said arms is removably fitted within coacting sockets formed in the head 45 and is supported at its free end by the member 46, the said shanks 53 being of such length as to extend through the guide member 48 to rest upon the member 46, as best illustrated in Figs. 1 120 and 2 of the drawings. The exhibit supporting arms 52 are thus detachably connected with the head 45 and are supported for rotative movement thereon by the shanks 53.

Disposed for detachable connection with each of the arms 52 is a suitable card 56 indicated in detail in Fig. 4 of the drawings,

the said card being adapted to bear suitable indicia for display. In this connection, it is desired to state that while I have illustrated the employment of cards in connection with my improved device, still, I do not wish to be limited to their use, since the arms 52 may be caused to support other articles for display and the construction which I provide is, therefore, equally applicable for use in exhibiting various classes and kinds of objects. The cards 56 may be of any suitable character and are of a transverse width to extend throughout the major portion of the length of the arms 54, the said cards being each formed, adjacent one side edge thereof with a vertically arranged slot 57 which is arranged contiguous to one end of the card. Each of the cards 56 is also provided medially thereof with an opening 58. 20 In connecting the cards 56 with the arms 54, the arms are passed through the slots 57 and the free terminals thereof are inserted through the openings 58, the shoulders 55 engaging within the said openings to maintain the cards in position as illustrated in Fig. 1 of the drawings.

Each of the cards 56 upon opposite sides of the longitudinally extending opening 57 formed therein is provided with longitudinally extending parallel folds or creases 59 to provide, substantially, an intermediate offset portion 60 in which the slot 57 is arranged. The arms 54 are disposed to extend loosely through said slots 57 and it will be observed that the cards 56 are thus mounted to pivot in a vertical plane upon the shoulders 55 of the said arms, this being for a reason which will be presently described.

40 As shown in Fig. 1 of the drawings, the cards 56 are supported to depend from the arms 52 in radial relation to the head 45 and will, when the device is in operation, be rotated with the head through the medium of the clock works 11. Secured to the base 10 in spaced relation to the post 38 is a second post or upright 61 to the upper end of which is secured in any suitable manner a resilient finger or detent 62. The finger 62 may be 45 formed from a length of suitable resilient wire and is laterally curved adjacent its outer extremity as best shown in Figs. 2 and 3 of the drawings, to extend into the path of the cards 56, the free terminal of the said finger being disposed to engage the adjacent side margins of the cards 56 in substantial alignment with the arms 54, as shown in Fig. 1 of the drawings.

It will be noted that the finger 62 is arranged upon one side of and in advance of the vertical axis of the head 45 and is disposed to engage the outer edge of each of the cards 56 in a plane with the adjacent side of the head to consequently arrest or

restrain each of said cards relative to the 65 rotation of the head 45 in substantially the same plane. It will now be seen that as the head 45 then continues to rotate and the pivot point of each of said cards, or the point where the shank of the arm carrying 70 the card engages the head, is moved away from the finger 62, the adjacent side edge of each of said cards will be caused to clear the free end of the finger to effect the release of the card. Preferably, the free 75 extremity of the finger 62 is curved longitudinally in the direction of rotation of the cards 56 so that as the cards are thus moved by the head 45, they will slide freely upon the said finger to be released. 80

It will be recalled that the head 45 is preferably rotated at a relatively slow rate of speed so that as each of the cards 56 moves into position in engagement with the finger 62, the said cards will be detained in 85 position for display, a corresponding length of time so that an observer will have ample opportunity to read any indicia appearing upon the cards, it, of course, being understood that when the cards are thus each detained by the finger 62 which in turn, will serve to arrest the outer extremity of the arm carrying the card, the shank of said arm will rotate or pivot within the sockets of the head as the head continues in its 90 rotary movement.

Particular attention is now directed to the peculiar construction by which I effect the automatic reversal of each of the cards 56 upon their release by the finger 62, or in other words, the means by which each of the arms 52 is caused to swing through an arc of substantially 180° to pass through a vertical plane at substantially right angles to the observer so that the side of the card 105 carried by each of said arms opposite to that exhibited under restraint of the finger 62, will be presented for view in substantially the same vertical plane occupied by the adjacent face of the next succeeding card 110 then engaged by the said finger. To effect this result, I so position the guide member 48 relative to the member 50 of the head 45, that the openings formed in the member 48 and receiving the free terminals of the 115 shanks 53 of the exhibit supporting arms, are disposed slightly upon one side of and out of vertical alignment with the openings formed in the member 50. Consequently, the inner extremities of the said shanks are 120 correspondingly moved to one side to dispose the shanks of the arms each in a plane at an angle to the axis of the shaft 43.

To further consider this peculiar mounting of the arms 52 it may be stated in other words, that one socket of each pair of sockets receiving one of the shanks 53 of said arms is disposed in a vertical plane upon one 125

side of the other socket of each of said pairs. Consequently, when the arms 54 are swung upon the head 45 to move through an arc of substantially 180°, they will move in a plane 5 tilted from the horizontal in a degree corresponding relatively to the inclination of the said shanks from the vertical.

It will be noted that the resilient finger 62 is arranged to so engage the cards 56 that the outer extremities of the arms 52 will be detained slightly in advance of and upon one side of the highest point in the plane in which the said arms travel so that when the head 45 rotates to a position to release each of said cards, the arms will, by gravity, automatically pivot upon the head 45 to swing to the lowest point of their movement in such plane. When so released the arms will pass through a plane at substantially right angles to the observer and accordingly present the reverse side of each card from that previously displayed under restraint of the finger 62, to view in substantially the same plane with the next succeeding card then engaged by the said finger. This will be best understood upon reference to Fig. 1 of the drawings, and I consider this a very important feature of the present invention, since the cards 56 are thereby, through the action of gravity, automatically reversed, while the means employed for effecting this result, is obviously exceedingly simple.

Since, as above stated, the members 48 and 50 are loosely mounted upon the shaft 43 and are clamped in rigid position thereon by the nut 51, it will be noted that the said members may be adjusted upon the shaft with relation to each other to simultaneously position the sockets formed in the member 48 from the vertical relative to the sockets formed in the member 50 and accordingly adjust the inclination of the shanks 53. Since the arms 52 are caused to pivot by gravity upon the head 45, through the inclination of said shanks, it will be observed that in providing for the adjustment of the members 48 and 50, the arms may be adjusted to travel each in a plane tilted a greater or less degree from the horizontal. In this way, and as will be clear, a further adjustment is had of the rapidity with which the arms will pivotally swing upon the head 45 to reverse the position of the 55 cards.

This adjustment by which the rapidity of the pivotal movement of the arms 52 is controlled is, as will be clear, a decided advantage, since where the arms 52 are caused to support relatively light articles such as cards as illustrated in the drawings, the member 48 may be adjusted to so incline the shanks 53 that the said arms when released will quickly swing upon the head 45 so that

a correspondingly increased length of time 65 will be had in which to observe the reverse side of each of the cards which is then brought into view. However, where the arms 52 are caused to support relatively heavy articles, it will be seen that the said 70 arms will more quickly gravitate than in the instance given where cards are employed, and consequently, pivot upon the head 45 with undue force. In such instance, the member 48 may be adjusted accordingly, so 75 that the arms 52 will each travel through their arcuate path at the desired speed.

Since the arms 52 when pivoting upon the head 45 in the manner heretofore described, move each in a plane tilted with respect to 80 the head or with respect to the horizontal, attention is directed to the construction whereby the cards 56 are disposed to maintain their proper position with relation to the horizontal at the time of display, both 85 when restrained by the finger 62 and when swung to the opposite side of the head immediately after their release by the said finger. It will be noted upon particular reference to Figs. 1 and 3 of the drawings, that 90 as the head 45 is rotated, the card 56 engaged by the finger 62 will be restrained to move the arm carrying the said card pivotally upon the head 45 against its normal tendency to gravitate to substantially the 95 highest point of movement of said arm in the plane in which it travels. In order to maintain its proper position with relation to the vertical, the card 56 carried by the said arm and engaged by the finger 62 must, 100 therefore, pivot in a vertical plane as the arm carrying the said card moves from its lowest point of movement toward its highest point of movement, and until it is released by the said finger. The presence of the 105 shoulders 55 upon the arms and pivotally receiving the cards and the provision of the vertically arranged slots 57 will now be apparent. As each of the cards 56 is restrained by the finger 62, the cards will, 110 through the action of gravity tending to move them to normally assume the vertical, pivot upon the shoulders 55 to consequently maintain their proper position, the intermediate portions of the arm 52 moving within 115 the slots 57 as the cards are thus pivoted. It, of course, follows that when the arms are released to reverse the cards, the cards will pivot upon their arms to consequently assume a horizontal position when so reversed. 120

From the preceding description, it will be seen that in the construction which I provide, the action of gravity is employed both for shifting the cards to effect the reversal thereof and for automatically maintaining 125 the cards in proper normal position with relation to the vertical at the time of display. Obviously, this is an advantageous arrange-

ment, since the necessity of providing mechanical means for effecting the same results, which means heretofore have been expensive and cumbersome, is obviated. Furthermore, it is to be observed that the cards are positively connected with the arms 52 to move therewith while owing to the presence of the slots 57 adjacent the inner margins of the said cards, the possibility of one card interfering with adjacent cards will be eliminated.

Normally, the arms 52 rest at the lowest point of their movement in the plane in which they travel as shown in Fig. 1 of the drawings, and as the head 45 rotates to successively bring the cards 56 into engagement with the finger 62, the cards in the rear of the card engaged by the said finger, upon being brought under the restraining influence of the finger, engage each other and, as the head then continues to rotate, are swung upon the head to the highest point of their movement in said plane. Consequently, as each card is so moved and is brought into direct contact with the finger to be released thereby, it will swingingly gravitate upon the head to reverse its position as previously described. By this construction, it will be observed that the action of my improved device is entirely automatic and that under the influence of the clock works 11, the cards 56 will be continuously exhibited.

In this connection, it is desired to bring attention to the attention device 36 and its rate of rotary movement with relation to that of the cards 56. Since, such of the cards 56 presented for display will, for the greater portion of the time be held stationary so far as their pivotal movement upon the head 45 is concerned, the advantage of employing the attention device, the movement of which is continuous and at a rate of speed relatively much faster than the rotary movement of the head 45, will be clear. For instance, the attention of a person passing the device at a time when the cards presented for display were in the position shown in Fig. 1 of the drawings and were, relatively speaking, stationary, might not be attracted to the said cards but it will be seen that notwithstanding this fact, the attention device bearing the word "Look" would, under ordinary circumstances, arrest the attention of the observer who would then naturally peruse the cards displayed. I, therefore, regard the provision of the attention device as a very important feature of the present invention as well as the feature of arranging said device to rotate continuously at a relative speed greater than the rotary movement of the cards 56.

In Fig. 9 of the drawings, I have illustrated a slight modification of the invention wherein the arms 52 are caused to pivot-

ally gravitate upon the head 45 by inclining 65 the shaft 43 with relation to the vertical, the post 38 and the guide arm 40 in such instance, being arranged upon one side of and out of alinement with the drive shaft 20. As will be clear, such inclination of the head 45 as shown in this figure will cause the arms 52, through the action of gravity, and upon being released by the resilient finger 62 to normally swing upon the head 45 in a manner which, in view of the preceding description, will be entirely clear, to effect the reversal of the cards. In thus inclining the shaft 43, the members 48 and 50 may be so positioned with relation to each other that the openings formed in said members will 80 aline, when, of course, the shanks 53 of the arms 52 will be supported in a plane parallel to the axis of the said shaft.

Otherwise, the construction disclosed in this modification is similar to that found in 85 the preferred form of the invention and a further detailed description, will, therefore, not be given.

Having thus described my invention, what I claim and desire to secure by Letters 90 Patent is:—

1. A device of the character described including a rotatably mounted standard having a shaft provided with a head formed with a bearing member, a guide member arranged in spaced relation to the bearing member, a sleeve bearing at one end upon the guide member, and a terminal member resting upon the opposite end of the sleeve, means carried by the shaft and engaging 100 said last mentioned member for clamping the members of the head upon the shaft to rotate therewith, an exhibit supporting member swingingly connected to the head and including an arm having a shank formed thereon, the said shank being pivotally connected with the head and extending through said terminal member and the guide member to rest upon the bearing member, the guide member being adjustable 110 relative to the bearing member for tilting the shank of the exhibit supporting member at an angle to the vertical to cause the said exhibit supporting member to gravitate upon the head, and means arranged to operatively restrain the said exhibit supporting member to be swung upon the head against its tendency to gravitate by the rotation of the standard.

2. A device of the character described 120 having a standard provided with a head including a guide member, an exhibit supporting member carried by the head and including an arm having a shank formed therein, the said shank being pivotally connected 125 with the head and engaged by said guide member, means for adjusting the guide member upon the standard whereby to move

5 said shank into angular relation to the axis of the said standard for causing the exhibit supporting member to gravitate upon the head, and means arranged to operatively restrain said arm to be pivoted upon the head against its tendency to gravitate by the rotation of the standard.

10 3. A device of the character described including a rotatably mounted standard, means mounted upon the said standard and gravitating to swing thereon in a fixed plane tilted from the horizontal with the said means adapted to carry an exhibit, and means arranged to operatively restrain the 15 said first mentioned means to be swung against its tendency to gravitate by the rotation of the standard with the said first mentioned means movable to be freed from the said restraining means in the said plane.

20 4. A device of the character described including a rotatably mounted standard, means swingingly mounted upon said standard and adapted to support an exhibit, a member engaged with said means and adjustable upon the standard for tilting the said means to swingingly gravitate upon the standard, and means for operatively restraining said first mentioned means to be swung against its tendency to gravitate by 25 the rotation of the standard.

30 5. A device of the character described including a rotatably mounted standard, exhibit supporting means swingingly connected to the standard to gravitate thereon, means carried by said standard for adjusting the inclination of said first mentioned means relative to the standard for regulating the gravitating movement thereof, and means arranged to operatively restrain the 35 said first mentioned means against its tendency to gravitate by the rotation of the standard.

40 6. A device of the character described including a rotatably mounted standard, said standard including a head providing a bearing member, a guide member arranged to cooperate with the bearing member, and a member spaced from the guide member, an exhibit supporting element swingingly connected to the head and including an arm having a shank formed thereon with the shank passing through said last mentioned member and through the guide member to rest upon the bearing member, means carried by the standard for adjusting the guide member relative to the bearing member whereby to tilt the said exhibit supporting member to swingingly gravitate upon the head, and means arranged to operatively restrain the exhibit supporting element to be 45 temporarily moved against its tendency to gravitate by the rotation of the standard.

50 7. A device of the character described including a rotatably mounted standard, ex-

hibit supporting means mounted upon the 65 said standard and gravitating to swing thereon in a fixed plane tilted from the horizontal for reversing an exhibit carried by said means, and means arranged to operatively restrain the said first mentioned means to be 70 swung against its tendency to gravitate by the rotation of the standard.

75 8. A device of the character described including a rotatably mounted standard, a motor for rotating said standard, a rotatable governor for the motor mounted to rotate at a relative speed greater than that of the standard, and an attention device carried by the governor.

80 9. A device of the character described including a rotatably mounted standard, a member mounted to swing thereon and adapted to receive an exhibit, a motor arranged to rotate the standard, means arranged to operatively restrain the said member to be temporarily swung by the rotation of the standard, and a rotatably mounted attention device operatively connected with the motor and mounted to continuously rotate at a relative speed greater than that of 85 the standard.

90 10. A device of the character described including a rotatably mounted standard, an exhibit supporting member mounted to swingingly gravitate thereon, means arranged to operatively restrain said member to be temporarily swung against its tendency to gravitate by the rotation of the standard, and means for regulating the rapidity 95 of the gravitating movement of the said 100 member.

105 11. A device of the character described including a rotatably mounted standard, an exhibit supporting member swingingly mounted upon the standard and provided with a shank, means engaging the shank for tilting the said member to swingingly gravitate upon the standard, and means arranged to operatively restrain the said member to be temporarily swung against its tendency to 110 gravitate by the rotation of the standard.

115 12. A device of the character described including a rotatably mounted standard, means swingingly mounted upon said standard and adapted to carry an exhibit, means for tilting the said first mentioned means for causing the said means to swingingly gravitate upon the standard in a plane tilted from the horizontal, and means arranged to operatively restrain the said first mentioned 120 means to be swung against its tendency to gravitate by the rotation of the standard.

125 13. A device of the character described including a rotatably mounted standard, an exhibit supporting member mounted upon the standard and gravitating to swing thereon in a plane tilted from the horizontal, an exhibit freely connected to the said member,

and means arranged to operatively restrain the said member to be moved against its tendency to gravitate by the rotation of the standard, the said exhibit being supported to 5 pivot upon the said member for maintaining its position relative to the vertical as the said member is swingingly moved upon the standard.

14. A device of the character described 10 including a standard, an exhibit supporting member carried by the standard and swingingly connected thereto, and means for tilt-

ing the said means to shift the axis thereof relative to the axis of the standard for causing the said member to swingingly gravitate 15 upon the standard in a plane tilted from the horizontal.

In testimony whereof I affix my signature in presence of two witnesses.

HORACE G. BAKER. [L. S.]
